UNITED STATES PATENT OFFICE

138,578

DESIGN FOR A RADIO REMINDER

Samuel A. de Waltoff, Los Angeles, Calif., assignor of one-third to Henry K. King and one-third to David A. Bernstein, both of Los Angeles, Calif.

Application May 23, 1944, Serial No. 113,720

Term of patent 7 years

(Cl. D42—1)

To all whom it may concern:

Be it known that I, Samuel A. de Waltoff, a citizen of United States and residing at Los Angeles, in the county of Los Angeles and State of California, have invented a new, original, and ornamental Design for Radio Reminder, of which the following is a specification, reference being had to the accompanying drawing, forming a part thereof.

The article is in the nature of a thin cardboard or binder's board and is without appreciable thickness.

Fig. 1 is a plan view of a radio reminder, showing my new design; and

Fig. 2 is a plan view of the opposite side shown in Fig. 1.

I claim:

The ornamental design for a radio reminder, as shown and described.

SAMUEL A. DE WALTOFF.
